UNITED STATES PATENT OFFICE.

RICHARD B. LANUM, OF CIRCLEVILLE, OHIO.

RECEIVING AND BURIAL VAULT.

SPECIFICATION forming part of Letters Patent No. 284,027, dated August 28, 1883.

Application filed January 4, 1883. (No model.)

To all whom it may concern:

Be it known that I, RICHARD B. LANUM, of Circleville, in the county of Pickaway and State of Ohio, have invented a new and Improved Receiving and Burial Vault, of which the following is a full, clear, and exact description.

The object of my invention is to provide a new and improved mortuary or receiving and burial vault for receiving the remains of the dead temporarily or permanently.

The invention consists in a mold for forming the chambers, which mold consists of two wedge-shaped pieces and a semi-cylindrical top piece, which pieces are all surrounded by a layer of paper for the purpose of obtaining smooth surfaces of the chambers.

Reference is to be had to the accompanying drawings, forming part of this specification, 20 in which similar letters of reference indicate corresponding parts in all the figures.

Figure 1 is a front end elevation of my improved receiving-vault, showing one door swung open. Fig. 2 is a cross-sectional elevation of the receiving-vault and of the mold for forming the chambers in the same. Fig. 3 is a longitudinal sectional elevation of the vault. Fig. 4 is a longitudinal sectional elevation through one of the chambers, showing the 30 mold for forming the chamber.

The vault or mortuary A can be made oblong, square, oval, or circular, as may be desired; but preferably it is made oblong with a rounded roof. A series of chambers, B, each 35 of sufficient size to receive a body, are formed in the vault, the said chambers being closed at one end and open at the other end, the edges of the open end being beveled to receive a gate, C, which fits closely within the end of the 40 chamber. To that end of the vault at which the open ends of the chambers are formed a frame, D, is held by means of anchors E, and to the said frame D the doors F are hinged. After the bodies have been placed into the 45 chambers B the gates C are secured in the ends of the chambers, and are cemented or otherwise packed to form close joints. The air can then be removed from the chamber by means of some suitable device. The body will then 50 not be subjected to the action of the air, and will not be decomposed. The entire vault is to be built of cement, all in one piece, so that there will be no joints or seams. For forming the chambers I use a mold formed of two 55 wedge-shaped pieces, J K, on which a semi-

cylindrical piece, L, rests. The bottom piece, K, increases in thickness toward the inner end of the chamber, and the upper piece, J, decreases in thickness toward the inner end of the chamber. A layer of smooth paper or other flexible material, M, is placed around the top and sides of the mold-pieces J, K, and L, and then the cement is packed around the upper covering. After the cement has settled and hardened, the wedges J and K, the 60 semi-cylindrical piece L, and the paper coverings are withdrawn, and will leave a smooth-surface chamber in the vault.

The vault can be ornamented very elaborately, if desired, and can be made in any 70 style of architecture.

The paper covering M may also cover the bottom of the mold, if desired, and thus leave the bottom surfaces of the chambers as smooth as their tops and sides.

Having thus described my invention, what I claim as new, and desire to secure by Letters Patent, is—

1. A burial-vault molded into shape, with a number of coffin-chambers entirely separated from each other, each provided with an opening at one end, and each having a gate adapted to be hermetically sealed, as shown and described.

2. The combination, with a vault, A, provided with chambers B, having the edges beveled at the open ends, of the gates C, fitting in the ends of the said chambers, substantially as herein shown and described, and for the purpose set forth.

3. The combination, with a vault, A, having chambers B, of the frame E and the doors F, hinged to the same, substantially as herein shown and described, and for the purpose set forth.

4. A mold for forming chambers in cement receiving-vaults, consisting of the wedge-shaped pieces J and K and the semi-cylindrical piece L, substantially as herein shown and described, and for the purpose set forth.

5. A mold for forming chambers in receiving-vaults, formed of wedge-shaped pieces J and K, the semi-cylindrical piece L, and the flexible covering M, substantially as herein shown and described, and for the purpose set forth.

RICHARD B. LANUM.
